UNITED STATES PATENT OFFICE.

R. PAUL HEMMING, OF PHILADELPHIA, PENNSYLVANIA, ASSIGNOR TO JOHN H. BROMLEY, JOSEPH H. BROMLEY, AND EDWARD BROMLEY, ALL OF SAME PLACE.

DESIGN FOR A CARPET.

SPECIFICATION forming part of Design No. 14,357, dated October 23, 1883.

Application filed August 25, 1883. Term of patent 3½ years.

To all whom it may concern:

Be it known that I, R. PAUL HEMMING, a citizen of the United States, and a resident of Philadelphia, Pennsylvania, have invented a new and Improved Design for Carpets, Rugs, &c., of which the following is a specification.

The nature of my invention is fully set forth in the accompanying photographic illustration, to which reference is made.

What I claim as my invention is—

10 The design for carpets and rugs, as shown.

Witnesses: R. PAUL HEMMING.

J. GORDON SHOWAKER,
WILLIAM JARDEN.
